DISPLAY RACK

Richard R. Garcia, Laredo, Tex., assignor to Miracle
Candle Company, Laredo, Tex.

Filed July 17, 1972, Ser. No. 272,374

Term of patent 14 years

Int. Cl. D20—02

U.S. Cl. D6—25

FIG. 1

FIG. 2

FIG. 3

FIG. 1 is a top plane view of the display rack of my invention;

FIG. 2 is a side elevational view thereof, the side not shown being identical to the side illustrated;

FIG. 3 is a side elevational view of the display rack of my invention, similar to the side elevational view shown in FIG. 2, but rotated through an angle of 45 degrees; and

FIG. 4 is a bottom view of the display rack of my invention.

I claim:

The ornamental design for a display rack, as shown.
